PAUL H. HORWITT, OF BROOKLYN, NEW YORK, ASSIGNOR TO INDEPENDENT PAPER MILLS, INC., OF BROOKLYN, NEW YORK, A CORPORATION OF NEW YORK.

STAND FOR NAPKINS AND THE LIKE.

Application filed July 6, 1923. Serial No. 649,893.

To all whom it may concern:

Be it known that I, PAUL H. HORWITT, a citizen of the United States, and resident of the borough of Brooklyn, county of Kings, 5 city and State of New York, have invented certain new and useful Improvements in Stands for Napkins and the like, of which the following is a specification.

My invention relates to stands for stacks 10 of napkins or their equivalent and more particularly to stands for paper napkins, paper towels, toilet paper and the like and has for its object to provide a novel and improved arrangement whereby a supply of 15 such napkins, towels, toilet paper or the like, stacked in a novel manner, is supported in such a way as to facilitate the removal of individual napkins or their equivalent and to avoid the necessity for careful manipulation 20 to avoid waste which results from the unintentional withdrawal of more than one napkin or their equivalent when but one is desired. Other more specific objects will appear from the description hereinafter.

25 In the accompanying drawings which illustrate an example of the invention without defining its limits, Fig. 1 is a sectional elevation of the novel stand with the novel stack of napkins or their equivalent thereon; 30 Fig. 2 is a plan view thereof and Fig. 3 is a plan view of the stack of napkins or its equivalent.

The present invention consists in folding the napkins or their equivalent into ob- 35 long rectangular shape and then arranging the same in the form of a stack in which adjacent napkins extend at right angles to each other with their contiguous ends overlapping so that the complete stack, when 40 viewed from above, has the form of a squared rectangle as shown in Fig. 3. With this arrangement there is always a terminal napkin which lies at the upper end of the stack and is free to be removed therefrom. 45 The latter is combined with a holder and with a member located at one end of the stack and having slots disposed in registry with one end of each series of napkins com- 50 posing said stack so that as each successive napkin becomes the terminal napkin its one end will be opposite a slot of said member through which it may be readily withdrawn without disturbing any of the other napkins in the stack.

55 In its illustrated form the stand com-

prises a base 5 from which a pedestal 6 rises as shown in Fig. 1, said pedestal being provided at its upper end with a plate or other support 7 upon which the stack of napkins is adapted to rest. The stack comprises successive groups of four napkins a , a' , a^2 and a^3 in which the four napkins extend at right angles to each other and have their contiguous ends overlapping. The stack thus consists of four series of napkins a , a' , a^2 and a^3 , respectively, which extend throughout the stack and each have free ends a^4 pointing in the same direction in each series. A member 8 is located at one end of said stack and in the illustrated example rests 70 upon the upper end thereof as shown in Fig. 1, said member being provided with slots 9, 9^a, 9^b and 9^c located in registry respectively with the free ends a^4 of the series of napkins a , a' , a^2 , and a^3 as shown in Fig. 75 2. In the preferred arrangement flanges 10 depend from the member 8 and enclose the stack of napkins or their equivalent as indicated in Fig. 1.

In practice the end a^4 of the terminal 80 napkin which, in the illustrated example, is one of the series a , is located in registry with the slot 9 of the member 8 and because of the pressure exerted by the latter upon the stack is given a slight upward turn as shown in Fig. 1 which makes said end readily accessible through said slot 9. This terminal napkin a may thus be readily removed through the slot 9 by exerting a pull upon its end a^4 without in any way disturbing the other napkins of the stack. As the napkin a is thus removed one of the napkins a' will become the terminal napkin and its end a^4 will similarly be turned upwardly through the slot 9^a of said member 8. In 85 the same way a napkin a^2 and a^3 will successively become the terminal napkin and have an end a^4 turned upwardly through the slots 9^b and 9^c respectively. In this way individual napkins from each series 100 may be successively removed through the slots 9, 9^a, 9^b and 9^c without disturbing the remainder of the stack.

It will be understood that when I speak herein of napkins I intend to include all equivalents of paper napkins which might be displayed for use in a stand of the described form. It will further be understood that the construction and arrangement of the latter may be other than that illustrated.

in the drawings and that in some cases the member 8 may be stationary while the support 7 or its equivalent progressively moves toward the same as the terminal napkins or their equivalent are removed; in the latter form the device might be used in a position inverted with respect to that illustrated in the drawings.

The device provides for the ready removal of individual napkins in a simple manner and does away with indiscriminate handling of the napkins or their equivalent so that the latter are protected against contamination and are maintained in a sanitary wholesome condition.

Various changes in the specific form shown and described may be made within the scope of the claims without departing from the spirit of the invention.

20 I claim:

1. The combination of a holder, a stack of sheets combined therewith, said sheets alternately extending at right angles to each other and having their contiguous ends overlapping and a member located at one end of said stack and having slots in registry with the free ends of the sheets of said stack

through which a terminal sheet may be removed from said stack.

2. The combination of a holder, a stack of paper napkins or the like consisting of napkins or the like alternately extending at right angles to each other and overlapping at contiguous ends and a member adapted to exert a pressure upon said stack and having slots in registry with one end of each series of napkins or the like in said stack through which a terminal napkin or the like may be removed from said stack.

3. The combination of a holder, a stack of paper napkins or the like consisting of napkins or the like alternately extending at right angles to each other and overlapping at contiguous ends, a member resting upon said stack and having slots in registry with one end of each series of napkins or the like in said stack through which a terminal napkin may be removed from said stack and flanges depending from said member and enclosing said stack.

In testimony whereof I have hereunto set my hand.

PAUL H. HORWITT.
